UNITED STATES PATENT OFFICE.

JUSTUS HATTEMER, OF WEST NEW YORK, NEW JERSEY, ASSIGNOR TO HARDMAN, PECK & COMPANY, OF NEW YORK, N. Y., A CORPORATION OF NEW YORK.

FALL-BOARD FOR PIANOS.

No. 902,293.

Specification of Letters Patent.

Patented Oct. 27, 1908.

Application filed May 15, 1908. Serial No. 433,109.

To all whom it may concern:

Be it known that I, JUSTUS HATTEMER, a citizen of the United States, residing at West New York, in the county of Hudson and State of New Jersey, have invented certain new and useful Improvements in Fall-Boards for Pianos; and I do hereby declare the following to be a full, clear, and exact description of the invention, such as will enable others skilled in the art to which it appertains to make and use the same.

This invention relates to fall boards for pianos, and similar musical instruments, and has for an object to provide a fall board 15 folding in improved manner within the case.

A further object of the invention is to provide a fall board folding within the minimum amount of space back of the normal closed position of the fall board.

With these and other objects in view, the invention comprises certain novel constructions, combinations and arrangements of parts, as will be hereinafter fully described and claimed.

In the drawings:—Figure 1 is a perspective broken view of the fall board associated with a conventional piano case. Fig. 2 is a view in vertical transverse section of the improved fall board associated with a piano 30 case in closed relation showing in dotted lines the first movement of the opening. Fig. 3 is a vertical transverse sectional view of the improved fall board folded and open.

Like characters of reference designate corresponding parts throughout the several views.

In the making of player pianos it is found necessary or at least highly desirable to utilize every possible inch of space within the case, and for such purpose it is desirable to produce a fall board which will occupy but a very small amount of space when folded. For this purpose the fall board here shown comprises a substantially L-shaped portion 45 10 hinged by pivoting at the pivot point 11. At the normal outer edge the portion 10 is provided with hinges 12 to which is hinged a portion or strip 13 in such position as to normally extend outwardly substantially in 50 a plane with the longer leg of the L 10 as shown particularly in Figs. 1 and 2. The parts 10 and 13 may be provided with beads 14 and 15 respectively positioned to contact with each other when the fall board is extended and to hold in association with the

hinges 12 the strip 13 substantially in a plane with the portion 10.

To the normally under side of the strip 13 hinges 16 are secured and thereto is hinged a strip 17 which extends downwardly from the strip 13 when extended and in contact with the usual ledge 18 ordinarily found upon a piano case.

Adjacent the upper portion 19 of the case a strip or abutment 20 is rigidly secured 65 and between the normally upturned portion of the L-shaped member 10 and the said abutment a strip 21 is carried as by the hinge 22 and the upper edge of the portion 10. At the opposite ends of the piano case 70 grooves 23 are provided in any approved manner as by means of a strip 24 secured thereto as represented in the drawings. The strip 21 is provided with pintles 25 in its opposite ends positioned to move within the groove 23 which is set at an inclination as shown particularly in Figs. 2 and 3.

With the fall board closed as shown in full lines in Fig. 2 the first motion in opening the same is to raise the strip 13 upon the hinge 12 to the position shown in dotted line which permits the strip 17 to assume the position also shown in dotted lines, both strips 13 and 17 being then folded downwardly upon the top of the strip 10. The strip 10 is then lifted upon its pivot 11 and turned backwardly to the position shown in Fig. 3 with the then lowered edge of the strip 17 resting in the notch provided by the bead of the strip 21 which said notch or 80 groove also engages the under edge of the strip 20 when the fall board is extended. It will be seen that by the several folds employed the fall board is folded within a minimum amount of space as shown particularly in Fig. 3.

What I claim is:—

1. The combination with a piano case provided with grooves inclined to a vertical, of a fallboard hinged to the case, and a member hinged to the hinged member and provided with means engaging with and slideable in the inclined grooves.

2. The combination with a piano case, of a fallboard hinged to the case, of a member hinged to the outer extremity of the fallboard and provided with a hinge joint, and a member hinged to the fallboard and slideable relative to the case.

3. The combination with a piano case pro-

vided with grooves inclined to a vertical, of a fallboard hinged to the case, a member hinged to the fallboard and provided with pintles engaging and slidable within the 5 grooves, a member hinged to the outer edge of the fallboard and foldable thereupon, and a strip hinged to the hinged member and adapted to fold over and upon the adjacent edges of the hinged member and fallboard.

10 4. The combination with a piano case, of a fallboard member hinged thereto, of a member hinged to the fallboard member and extending upwardly, groove members at opposite ends of the fallboard, and means carried by the upwardly extending strip engaging and traveling in the groove member.

15 5. The combination with a piano case provided with grooves at opposite ends inclined to a vertical, of a fallboard member substantially L-shaped in transverse section hinged to the case, a strip hinged to the fallboard member and extending upwardly, means carried by the hinged strip traveling in the inclined grooves, and a hinged strip carried by the fallboard member.

20 6. The combination with a piano case provided with grooves at its opposite ends inclined to a vertical, of a substantially L-shaped fallboard member hinged in the case

adjacent its angle, and a strip hinged to the 30 upwardly extending portion of the fallboard member and provided with means traveling in the grooves.

7. The combination with a piano case, of a substantially L-shaped fallboard member 35 hinged to the case adjacent its angle, of a strip hinged to and extending above the L-shaped strip, means providing a movement of the strip downwardly and rearwardly when the L-shaped strip is moved, and a 40 strip hinged to the opposite extremity of the L-shaped member.

8. The combination with a piano case, of a substantially L-shaped fall board member hinged adjacent its angle, a strip hinged to 45 one extremity of the L-shaped member and extending upwardly, a strip hinged to the opposite extremity of the L-shaped member and extending outwardly, and a strip hinged to the last-mentioned strip and extending 50 downwardly.

In testimony whereof I affix my signature in presence of two witnesses.

JUSTUS HATTEMER.
